(57) **CLAIM**

The ornamental design for a mobile communications device attachment with camera, as shown and described.

DESCRIPTION

FIG. 1 is a front elevational view of a mobile communications device attachment with camera embodying the new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear-left-bottom perspective view thereof; and, FIG. 8 is a rear-left-bottom perspective view thereof, showing the mobile communications device attachment with camera in an environment of use.

The broken lines in FIGS. 1-7 depict a portion of the mobile communications device attachment with camera that form no part of the design. The broken lines in FIG. 8 are shown for the purpose of illustrating portions of the mobile communications device attachment with camera and environmental subject matter that form no part of the claimed design.
